UNITED STATES PATENT OFFICE

119,441

DESIGN FOR BATTERY PLIERS

William A. Sandy, Chicago, Ill., assignor to Duro Metal Products Company, Chicago, Ill., a corporation of Illinois

Application January 20, 1940, Serial No. 89,601

Term of patent 14 years

To all whom it may concern:

Be it known that I, William A. Sandy, a citizen of the United States, residing at Chicago, in the county of Cook and State of Illinois, have invented a new, original, and ornamental Design for Battery Pliers, of which the following is a specification, reference being had to the accompanying drawing, forming part thereof.

Fig. 1 is an elevational view of the front of battery pliers embodying my new design;

Fig. 2 is an elevational view of the rear of battery pliers embodying my new design;

Fig. 3 is an elevational view of the jaw end of battery pliers embodying my new design;

Fig. 4 is an elevational view of the handle end of battery pliers embodying my new design.

I claim:

The ornamental design for battery pliers, as shown.

WILLIAM A. SANDY.
